M. D. BRADLEY.

Broom Machine.

No. 80,443.

Patented July 28, 1868.

United States Patent Office.

MILES D. BRADLEY, OF BALLSTON SPA, NEW YORK.

Letters Patent No. 80,443, dated July 28, 1868.

IMPROVED MACHINE FOR CUTTING AND ASSORTING BROOM-CORN.

The Schedule referred to in these Letters Patent and making part of the same.

TO ALL WHOM IT MAY CONCERN:

Be it known that I, MILES D. BRADLEY, of Ballston Spa, in the county of Saratoga, and State of New York, have invented a new and improved Machine for Cutting and Assorting Broom-Corn and other similar articles; and I do hereby declare that the following is a full, clear, and exact description thereof, which will enable others skilled in the art to make and use the same, reference being had to the accompanying drawings, forming part of this specification.

Figure 1 is a side elevation of my improved machine.

Figure 2 is a top view of the same.

Figure 3 is a detail view of the cutter-wheel.

Figure 4 is a detail view of the internal gearing.

Similar letters of reference indicate corresponding parts.

The object of this invention is to cut and assort the different lengths of broom-corn, or other animal or vegetable substances which have longitudinal dimensions, and which are of a kindred character as to flexibility and other similar qualities, as, for example, rushes, flagging, horse-hair, reeds, rattans, or other like substances, which may require cutting and assorting previous to being wrought up into articles of use.

It consists of the mechanism and arrangement of devices set forth in the following:

A is a wooden drum, revolving upon a vertical shaft or equivalent gudgeons, $a a'$. The upper gudgeon, a' , has a bearing in the central boss b , forming part of the radial top frame $c c c d$, &c., as shown. This top frame is supported by the uprights $d d d d$, &c., which are affixed to and rise from the base-hoop B of the general frame, as shown.

The rollers $e^1 e^2 e^3 e^4 e^5 e^6 e^7 e^8 e^9$ are arranged parallel with the axis of the drum, and are in contact with and revolved by the drum when the latter is revolved. Belts, $n^1 n^2 n^3 n^4 n^5 n^6 n^7 n^8 n^9$, pass over the rollers, one-half of each belt being in contact with the drum, as shown.

The rollers are grooved, to keep the belts each at its proper distance from adjacent ones. The belts are of different lengths, and are arranged as follows:

The belt n^1 is on rollers e^1 and e^9 ; the belt n^2 is on the next longer roller e^2 and the roller e^8 ; belt n^3 is on the next longer roller e^3 and the roller e^9 ; belt n^4 is on the next longer roller e^4 and the roller e^8 , and so on, each belt being on a separate roller and the common roller e^9 , as shown at fig. 1.

The rollers decrease in length regularly around the drum, and it is by this arrangement of the belts and rollers that the different lengths of broom-corn and other materials having similar character are assorted, as will be shown.

The rollers have bearings in the radial slot i in the rim f of the top frame $c c c$, &c., as shown; and in the horizontal braces $g g g$, &c., affixed between the uprights $d d d$, &c., as shown.

The lower gudgeon, a , of the drum has a bearing in the foot-step h , which is a screw having a hollow end, to receive the said gudgeon, and a hand-wheel, j , for adjusting the drum up or down, when it is requisite to do so, when the height of the cutting-wheel D is adjusted to cut the different lengths of material generally longer or shorter.

The foot-step h works in a hollow thread in the centre of framing $c c c' c'$, &c., affixed within the uprights $d d d$, &c., as shown.

The cutting-wheel D is keyed on a shaft, E, which latter revolves in the adjustable step-bearing k , p being the hand-wheel for turning the same, and m being the hollow-threaded plate affixed to the uprights $d d$, holding the said bearing k .

o is a jam-nut, for screwing up against the plate m , to hold the bearing firmly.

q is a spring-bearing, affixed to the upright, d , as shown.

r is a bevel-pinion on the shaft E, which pinion engages with the bevel-wheel u , on the same shaft with the pulley G, as shown.

H is a projecting bearing for the shaft of the pulley and wheel.

The bevel-pinion r is not keyed firmly on the shaft E, but slides vertically thereon, being retained from turning on the said shaft, without transmitting motion thereto, by any suitable device, as that of a vertical feather on the shaft fitting a slot in the eye of the pinion, thus permitting the shaft to be adjusted up or down, without disengaging the bevel-gearing r and u.

Radial cutters, v v v v, are affixed on the periphery of the wheel D, as shown, and are formed with a curved or shear edge, that their action may be smooth and free from jar.

The arm W and disk W', which serve as a bearing for the cutters, are not affixed firmly to the upright, d, but slides thereon within the guide t', as shown, the arm W presenting a surface of contact to two sides of the upright, and is guided in its vertical movement by the said guide t'.

The cutter-wheel D is just above the disk w', forming part of the arm w affixed to the upright, d, as shown, and the said disk serves to hold the broom-corn or other material in an angle, as shown, so that the cutters may operate more effectively.

The drum is revolved by means of the toothed rim I, affixed to its under side, as shown, and the pinion J, keyed in the upper end of the shaft E. An arm-plate, t, serves to actuate the lower part of the broom-corn or other material forward, so as to prevent it from bending when being cut by the cutters.

The chutes K K K, &c., are hooked on the frame C, as shown, and serve to conduct the broom-corn or other material to the bins L, placed around the machine, at the lower extremities of the chutes, as shown.

The roller e^o has its bearings in pivoted plates, M N, which enable the belts to be slackened up when the machine is not in use, by turning the said plates and the roller outward.

The operation of the machine is as follows, and in the description of the said operation the broom-corn will be taken for the illustration thereof.

The attendant sits conveniently elevated and near to the roller e^o, holding in his lap a bundle of the corn to be cut and assorted. Taking the stalks, one at a time, he feeds them in between the roller e^o and the drum, as shown by the stalk indicated in red.

The stalk is fed in at a slight angle from the perpendicular, so that the bush will be seized by the belts and the roller, and the juncture of the brush and stalk is entered always at the same point on the roller e^o, which point is the lower part of said roller. The broom-corn is borne to the cutter, which cuts it, as shown, and the cut end falls to the floor. The bush and its remaining stalk are then borne by the drum until they pass from under all or a portion of the belts and are dropped into the upper part of the chute, which conducts them down to the bin, as shown. The operation of the belts in this respect is illustrated at fig. 1, where a bush of broom-corn is being held by the longest belt n¹. This bush will be held until it comes out at the last roller e^l, when it will be dropped into the proper chute. A bush of corn one size shorter would fall from the machine, after passing from under the roller n², for the end of the said bush would not be sufficiently long to be held against the drum by the belt n¹. A bush two sizes shorter is shown in the chute, it having fallen at the roller n², for the reason that it was not sufficiently long to be held to the drum by the belt n², and thus all around the drum the bushes of corn fall into the chutes set under each roller.

When this machine is used for assorting the different lengths of hair, any suitable feeding-apron, composed of vertical rollers, having cylindrical feeding-brushes, must be employed, or some other equivalent means of feeding in flexible materials in a vertical position.

The chutes can be unhooked and put anywhere when they are not in use.

The usual day's work in cutting and assorting broom-corn, as heretofore, is about one hundred pounds per hand. By my improved machine, I have cut and assorted one ton of broom-corn per day, though this was merely as a trial, and the result is somewhat greater than what would be the case in ordinary daily work.

It is simple, cheap, and effective, and supplies a want long felt by those who raise broom-corn or other articles of similar nature for market.

I claim as new, and desire to secure by Letters Patent—

1. The perpendicular drum A, the different-sized rollers e¹ e² e³, &c., and belts n¹ n² n³, &c., whether the said belts be flat or round, all constructed and operating together substantially as shown and described, and for the purpose set forth.

2. The cutters v v v v, shaft E, pinion J, and toothed rim I, whether the said rim be toothed externally or internally, and drum A, all constructed and operating together substantially as shown and described, and for the purpose set forth.

3. The chutes K K K, &c., in combination with the drum A, rollers e¹ e² e³, &c., and belts n¹ n² n³, &c., all substantially as and for the purpose shown and described.

4. The adjustable step-bearing h, in combination with the drum A, rollers e¹ e² e³, &c., belts n¹ n² n³, &c., all substantially as shown and described, and for the purpose set forth.

5. The bevel-gearing r u and pulley G, substantially as shown and described, in combination with the drum A and its belts and rollers, all as and for the purpose set forth.

6. Adjustable step-bearing k, in combination with the shaft E, cutter-wheel D, drum A and its rollers and belts, all substantially as shown and described, and for the purpose set forth.

The above specification of my invention signed by me, this 18th day of February, 1868.
